FOLLOW-UP PNEUMATIC SERVOMOTOR

Ralph D. Wyckoff, Pittsburgh, Pa., assignor to
Gulf Research & Development Company, Pittsburgh, Pa., a corporation of Delaware

Application November 19, 1946, Serial No. 710,745

5 Claims. (Cl. 121—41)

1

This invention relates to actuating devices and to controls therefor.

An object of the invention is to provide an actuating device, which, under the influence of a source of power, moves at a predetermined speed.

Another object of the invention is to provide an actuating device, which, under the influence of a motivating force, may move at any selected speed and which is so controlled as to neither substantially exceed said speed nor to fall substantially below said speed regardless of the degree of loading of said actuator.

A further object of the invention is to provide a servomotor including a power cylinder with a pneumatically actuated piston movable therein to drive a power shaft, and having valve means for regulating the flow of compressed gas into the cylinder to drive the piston, with orifice means cooperatively disposed relative to the exhaust of said cylinder to regulate the rate of exhaust therefrom and accordingly to regulate the speed of movement of the piston and its power shaft.

Still another object of the invention is to provide a pneumatic actuator system which is capable of typical servo action, and which, by means of a critical orifice device incorporated therein, is capable of attaining substantially constant though adjustable speed of operation over very wide ranges in load and gas supply pressure.

Another object of the invention is to provide a pneumatic actuator device having characteristics closely simulating a constant volume hydraulic system without the use of complex speed control devices, such devices being replaced by a simple orifice which may be adjusted at will.

Another object of the invention is to provide a pneumatic actuator in which the rest position of the operating piston may be controlled at will.

A further object of the invention is to provide a constant speed pneumatic actuator device which may be employed for the control of elevator and rudder flaps on dirigible high-angle bombs, where the hinge moments are of such magnitude as to preclude the use of electric motor drive due to excessive size and other considerations.

Other objects and advantages of the invention will become apparent from the following description of a preferred embodiment thereof as illustrated in the accompanying drawing, and in which,

Figure 1 is a sectional view of a pneumatic actuator according to the invention, showing in the lower portion thereof an actuator cylinder, pis-

ton and piston rod, and in the upper portion thereof illustrating the construction of a valve assembly for controlling the operation of the actuator.

Fig. 2 is an enlarged sectional detail view of a portion of the apparatus showing the exhaust manifold with its associated disc and regulating orifice.

Figure 3 is an enlarged sectional detail view of a portion of the exhaust manifold with alternative type of orifice which may be employed, and

Figure 4 is a sectional view of the right hand end of the valve section of Figure 1 when arranged for servo operation.

Pneumatic actuators of the type including a cylinder having a piston driven shaft, are employed in many and quite diverse applications. One such application is the type of pneumatic actuators particularly intended for the control of elevator and rudder flaps on dirigible high-angle bombs, where the hinge moments are of such magnitude, that is, of the order of 1000 pounds maximum thrust per pair, as to preclude the use of electric motor drive due to the excessive size of gear reducers and internal battery power requirements, as well as other considerations.

In such a dirigible high-angle bomb, the only practical source of self-contained motivating power comprises gas stored under pressure in suitable tanks. A further requirement of the actuator for the rudders and elevators is that their rate of angular deflection should at no time exceed a specified value which is of the order of 10 degrees per second, nor should the speed of operation fall below this specified rate. These requirements must, according to some specifications, be fulfilled regardless of the fact that the load on the actuator, that is, the hinge moments due to aerodynamic forces on the rudders and elevators, will increase by a factor approximately in the ratio of 25 to 1 at the end of the flight of the bomb as compared with the aerodynamic forces involved at release of the bomb.

Evidently such operation is characteristic of a hydraulic system in which the actuator cylinder is fed by a constant volume pump, but is the antithesis of the operation characteristic of normal pneumatic systems. A further and quite important requirement of the actuator system is the greatest possible simplicity so as to eliminate excess apparatus and all possible sources of failure.

The above is a summary of the problems to be solved in one particular type of application

of the present invention, but it will be understood that such summary is only by way of example, and that the invention may be employed in many types of applications which will readily occur to those skilled in the art.

Reference may now be had to the drawings in which like reference characters indicate similar parts throughout the several views. Figure 1 shows a conventional cylinder 2 held between suitable heads 4 and 6 by through-bolts 8. Operating within the cylinder chamber 10 is piston 12 carrying a conventional packing ring 14 constrained within a suitable circumferential groove 16 as is customary. The piston 12 is mounted upon a continuous piston rod 18 in such manner as to preclude leakage between the rod and the piston. Rod 18 operates through the cylinder heads 4 and 6, with suitable packing members 20 and 22 interposed in apertures 24 and 26 respectively in the cylinder heads. The piston rod 18 is terminated at each end by a suitable clevis arrangement at 28 and 30 whereby the load member may be attached, to be moved in one direction or the other as the piston 12 is reciprocated within the cylinder chamber 10.

Suitable ports 32 and 34 are provided in each cylinder head, to which are attached pipes 36 and 38 respectively, for conducting gas into and out of the cylinder, as the piston 12 is thus driven. The actuator cylinder is hence a conventional double-ended piston rod device, which, as gas is admitted through port 34, causes the piston 12 to move to the left, the leftward movement of the piston forcing any gas remaining in the cylinder chamber between the piston and the left cylinder head 4 out through port 32 and into the pipe 36. Similarly, when gas is admitted to the cylinder through the left hand port 32, the piston 12 will travel to the right, forcing any gas remaining in the cylinder chamber between the piston and the right cylinder head 6 out through port 34 and into the pipe 38.

It is thus apparent that the pipes 36 and 38 may serve as both gas inlet and gas exhaust pipes depending upon the desired direction of movement of the piston 12 and the piston rod 18. And it is also apparent that by means of a suitable valve, illustrated in the upper portion of Figure 1, the direction of movement of gas into and out of the cylinder 2 through the pipes 36 and 38 may be controlled at will.

As shown, there is a valve block 40 which comprises a fixed mounting for the entire valve assembly. The block 40 has a valve cylinder 42 extending therethrough, the pipes 36 and 38 extending through the block 40 and terminating in two accurately spaced valve ports 44 and 46 respectively leading into the interior of the cylinder 42. Two exhaust ports 48 and 50 lead to pipes 49 and 51 which are connected together by a pipe 52, terminating in an orifice employed herein. One form of critical orifice is shown in detail in Figure 2, and an alternative form in Figure 3. A supply pipe 70 supplies gas under high pressure P_3 to the system through port 72.

The valve rod 58 carries valve discs or pistons 60 and 62 lapped to close clearance in cylinder 42 which serve to close the ports 44 and 46 with a small overlap when the valve rod is longitudinally centered in the cylinder. Similarly lapped discs 64 and 66, which are also an integral part of the valve rod, serve to close the ends of the valve cylinder, thus confining the exhaust gas to the manifold 68, and providing the necessary pres-

sure equalization characterizing a balanced valve system.

With this valve arrangement, when the valve rod is moved to the right of center, as is shown in the view, high pressure gas from a supply pipe 70 enters through the central section port 72, and flows between the pistons 60 and 62, thence through port 46 to actuator conduit 38. At the same time, conduit 36, through valve port 44, is open to exhaust chamber port 48, to manifold 68, through critical orifice 56, to atmosphere.

Obviously, the connections of conduits 36 and 38 are reversed when the valve stem 58 is moved to the left of center. In the central portion of the valve stem 58, both valve ports 44 and 46 are closed, and no gas enters conduits 36 and 38 except leakage due to valve clearance. However, as will be seen below, such leakage becomes of no consequence as regards drift of the actuator piston position, and in fact for certain purposes some leakage may be desired.

Attention may now be invited to the critical dimensions of the orifice 56 and the contiguous conduits.

In the flow of gas through a sharp-edged orifice such as 56 in Figs. 2 and 3, the mass rate of flow will increase approximately as the square root of the pressure drop across the orifice until the linear velocity of flow, such as in feet per second, reaches the velocity of sound. The weight of gas flow through the orifice varies linearly with the pressure difference across the orifice when the pressure difference is such as to exceed this critical value. In this critical flow region the mass of exhausted gas is substantially proportional to the pressure difference across the orifice. Because of the mass-volume relationship of gases this effect results in a volume rate of efflux through the orifice which is substantially constant as measured at the high pressure side of the orifice. Neglecting certain modifying details it may be said that in the region beyond the critical point the pressure difference across the orifice may be increased many fold without increase of the volume rate of efflux of gas through the orifice, measured as volume of gas at the high pressure side of the orifice. Moreover, the pressure difference required to reach the critical value is relatively small. It is well known that if P_1 is the pressure at the input and P_2 the pressure at the output the critical velocity maximum efflux rate is reached when the ratio P_2/P_1 is approximately 0.5. In the case of a sharp-edged orifice discharging gas into the atmosphere at pressure $P_2=15$ pounds per square inch, a substantially constant rate of discharge expressed as volume per second at pressure P_1 is reached when P_1 is equal to or greater than about 30 pounds per square inch.

My invention makes use of the above phenomena in pneumatic servo mechanisms for the attainment of constant rate or constant velocity of operation. Thus a pneumatically driven piston 12, such as shown in the actuator of Fig. 1, may be made to operate at a substantially constant velocity provided the gas in the end of the cylinder 10 exhausting to the atmosphere is at a pressure P_1 equal to or greater than 30 pounds per square inch, and further provided the exhaust is effected through a thin-plate sharp-edged orifice 56 of small enough diameter relative to other conduits so that it alone provides substantially all of the throttling effect. Under these conditions there is constant volume rate of efflux at the pressure P_1 exhausting from cylinder

10, and such constant volume rate of efflux results in a constant velocity of motion of piston 12.

The requirement that the exhaust pressure P_1 within the cylinder 2 is always greater than the required critical pressure of 30 pounds per square inch, is attained by making certain that the actuating pressure P_3 , that is, the pressure of the gas entering through pipe 70, is always greater than the equivalent load pressure (P_4) plus 30 pounds. Thus, as an example in the case of the actuator illustrated:

Maximum load=1000 pounds

Piston 12 area=15 square inches

Equivalent load pressure=1000/15=66.6 lbs./sq. in.

Required $P_3 > 66.6 + 30 = 96.6$ lbs./sq. in. (approx.)

Hence the operating pressure P_3 may be adjusted say to 100 lbs./sq. in., since the 1000 pounds maximum load pressure on rod 18 was based on a reasonable though small factor of safety, whereupon the piston 12 will operate at constant velocity at all loads up to maximum. Furthermore, the supply pressure P_3 may exceed 100 lbs./sq. in. or may fluctuate in value above 100 lbs./sq. in. without affecting the constant velocity operation of piston 12.

By this expedient is attained a pneumatic actuator having characteristics closely simulating a constant volume hydraulic system without the use of complex speed control devices, such devices being replaced by a simple orifice which may be adjusted at will. The important requirements to assure proper operation of the critical orifice 56 are, (1) the circular orifice must be a sharp-edged hole in a thin plate, and (2) that it be placed in an entrance box 68 whose inside diameter is not less than about 15 times the diameter of the orifice 56, and (3) that there should be no exit nozzle following the orifice.

Figs. 2 and 3 show examples of a thin-plate sharp-edged orifice 56 which may be used. In Fig. 2 a cover plate 54 covers the opening of the exhaust manifold 68. The orifice 56 comprises a tapered opening having a sharp edge on the inner side and flared outward at a large angle. The same effect may be attained by means of the orifice shown in Fig. 3 in which the cover plate 54 is reduced in thickness over a central portion 75 in which the orifice 56 is located. It has been found that an orifice in the portion 75 behaves practically as a sharp-edged orifice if the portion 75 is of a thickness 0.032 inch or less. In both Figs. 2 and 3 the inside face of plate 54 should be substantially unbroken.

The rate at which the actuator piston operates may be controlled by the size of the opening 55. To this end the cover plate 54 with its orifice may be removably attached to the manifold 68 by means of screws 132 which clamp the cover plate to flange 133 of manifold 68. An orifice plate having the desired flow rate value may thus be attached to manifold 68.

The means for actuating the valve mechanism and the actuator piston may now be further described. Both ends of the valve rod 58 are provided with extensions to which are pinned soft iron plungers 74 and 76 which operate slidably within solenoid coils 78 and 80 respectively. The outer iron shells 82 and 84 serve as the outer magnetic circuit for the solenoids as well as protective housings, and provide mounting sleeves 86 and 88 whereby the solenoids are accurately aligned concentric with the axis of the valve cylinder.

The inner shell of each solenoid comprises a thin brass tube 90 which prevents iron to iron contact and consequent sticking in the annular air gap between the plungers 74 and 76 and the concentric pole face comprising the inner ends of the solenoid shell. At the outer end of each solenoid shell the magnetic circuit is completed by a pole piece comprising an iron core 92 and 94, having a smoothly sliding fit within the inner brass cylinders and fixedly attached to brackets which in turn are rigidly attached to guide 96, which slides smoothly in guide hole 98 bored through the valve block 40 with its axis parallel to the axis of the valve cylinder 42.

As is customary in solenoid design to improve the traction curve, the plungers 74 and 76 and pole pieces 92 and 94 are provided with conical faces and non-magnetic spacers 100 to prevent sticking. Pole pieces 92 and 94 are also provided with axial holes 102 through which non-magnetic valve rod extensions 104 and 106 of the rod 58 pass freely. The extensions 104 and 106 are adjusted to such length after assembly that the terminus of each is exactly flush with the outer ends of the pole pieces 92 and 94 and hence centered between the guide-rod end posts. Centering springs 108 and 110 are attached by screws 112 and bear on the extensions 104 and 106 with sufficient contact pressure to hold the valve stem 58 firmly centered between the guide-rod posts when the solenoid coils are not energized. With the valve rod so centered and restrained by springs 108 and 110, the valve rod 58 will partake of any motion of guide-rod 96 if the spring tensions are sufficiently great with respect to friction between the valve and the valve cylinder. With the valve guide-rod 96 in center position pole pieces 92 and 94 will be symmetrically located in their respective solenoids. If solenoid coil 80 be then energized through wires 114, it is evident that the plunger 76 will overcome the thrust of spring 110 on extension 106, with the result that the valve port 46 leading to conduit 38 will be supplied with gas pressure while at the same time conduit 36 will be opened to exhaust through ports 44, 48, conduits 49, 52 and orifice 56. This will urge piston 12 to the extreme left position and the rate at which piston 12 travels will be dependent only on the size of the orifice 56, provided the supply pressure in 70 is higher than the required critical pressure P_3 determined as previously stated. Orifice 56 may of course be made of such size as to give the desired rate of operation.

Similarly, with valve guide-rod 96 centered, the energization of solenoid coil 78 through wires 116 will reverse the valve action. And, clearly, when both solenoid coils are de-energized, the springs 108 and 110 will return the valve stem 58 and its discs 60, 62, 64 and 66 to center.

Control of the valve action other than by solenoid means may be rendered possible by moving off center the valve guide-rod 96, which carries the entire valve rod assembly. Thus rod 96 may be provided, for example, with a threaded extension 118 on which rotates a threaded adjusting nut or pulley 120 confined longitudinally between shoulders 122 forming a part of support 124 rigidly attached to cylinder block 40.

Thus the turning of wheel 120, as by the action of flexible cord 126-128 wound about the pulley face, will result in motion of the guide-rod 96 and of the valve rod 58 with consequent valving action. It will be shown below how this control may be used to provide servo action of the actu-

ator other than merely urging the piston 12 to extreme right or left rest positions as described above.

Referring now to Figure 1, in order to obtain servo-type action of the actuator, it is necessary that the motion of the piston rod 18 be transmitted back in a proportional manner to the guide-rod 96 of the valve assembly. An expedient manner of doing this in the present instance is by means of a suitable flexible cable 126 from attachment at a point on the left end of piston rod 18, over suitable guide pulleys 127, around pulley wheel 120 of the valve assembly, and back via return section of cable 128, pulley 130, to the right end of the piston rod 18. The cable is adjusted to be free of slack motion and may have customary tension adjustment or slack removing means not shown.

Any motion of the piston rod 18 will be transmitted to the guide-rod 96 of the valve assembly by means of the cable 126-128 running over threaded pulley 120, and thence to the valve rod 58 in the same sense, that is, a leftward motion of the piston rod 18 will move the valve rod 58 to the left by virtue of the particular arrangement illustrated. And the relative magnitude of motion of the piston rod 18 and the valve rod 58 will be determined by the diameter of the pulley 120 and the pitch of the threads on the end 118 of the guide rod extension. The determination of the proper pulley size for a particular case will become evident.

There may now be considered the case, by way of example, in which it is desired that the neutral position of the actuator piston 12 should be the midpoint of its stroke. Cable 126-128 may then be adjusted so that with solenoids de-energized the valve rod 58 is centered, that is, its discs 60 and 62 cover ports 44 and 46, when the actuator piston 12 is in the desired center position. This is ascertained best with the apparatus in operating position. If now, for example, the right solenoid coil 80 is energized from wires 114, port 46 will be opened and high pressure gas from input pipe 70 will flow via conduit 38 to move piston 12 to the left.

However, at the same time, because of the mechanical coupling between the actuator and the valve, the valve rod 58 will also be carried to the left, gradually closing ports 44 and 46 until when valve pistons 60 and 62 symmetrically cover their respective ports 44 and 46 the actuator becomes locked in the corresponding position, which, by proper adjustment of the coupling ratio, may be at the end of its maximum possible stroke as limited by the length of the cylinder. Now, if solenoid 80 is de-energized, spring 110 forces the valve rod 58 to center with respect to the valve guide posts on rod 96. Whereupon, since the valve guide assembly is now displaced to the left of the valve-port center, port 44 will be uncovered to high pressure gas from inlet pipe 70, and port 46 to exhaust, thus returning the actuator piston 12 to the right and carrying the valve guide also to the right. When the actuator has reached center, the valve guide will be found centered with respect to the valve ports and the actuator piston will lock in neutral position. Any tendency to drift from proper neutral, as by variation in loading or leakage at the valve will be corrected immediately by valve action. By making the valve-overlap on the valve ports small, the accuracy of position lock-in will be enhanced.

Having thus described the functional arrange-

ment of the valve and actuator, it will be evident that variations in design and functioning are possible. Thus, instead of a solenoid arrangement which is obviously a full-right, full-left control, one might provide for any desired type of stroke. Thus a screw adjustment may be used as in Figure 4 which shows the right hand end of the valve assembly of Figure 1. Like parts of Figure 4 carry the same numerals as in Figure 1. The solenoid (of Figure 1) is replaced by a sleeve 190 pressed into the end of the valve cylinder 40. The valve stem 106 may be threaded and provided with a keyway 196 into which projects a pin 192 to prevent its turning. Nut 200, retained between guide rod post 94 and its arm 194 will permit displacement of the valve rod from central position between posts 94 and 92 (Figure 1). The left hand end of the valve system may be similar to Figure 4 except that the rod 106 need not be threaded or keyed and no nut would be provided at this end.

Such displacement would be proportionately repeated in the power stroke of the actuator piston 12 and its position held under load. Thus the system is capable of typical servo action under control of nut 200 or any other control means by which this nut may be actuated. Moreover, by virtue of the critical orifice device, illustrated in detail in Figure 2, substantially constant though adjustable speed of operation may be obtained over very wide ranges in load and gas supply pressure. Evidently bell-crank and variable linkage couplings may be used to replace the flexible cable and pulley arrangement illustrated.

Although I have described a preferred embodiment of the invention in specific terms, it is to be understood that various changes may be made in size, shape, materials and arrangement without departing from the spirit and scope of the invention, as claimed herein. Furthermore, my invention may be employed for a variety of uses other than that of actuating the control surfaces of a dirigible bomb as mentioned, examples of such uses being automatic door closers, brake mechanisms, ship's rudder controls, throttle and valve controls, and many others in which constant speed of operation is desirable.

What I claim as my invention is:

1. A pneumatic actuator comprising a cylinder having gas inlet and outlet ports, a piston movably disposed in said cylinder for movement under the influence of gas admitted to said cylinder through said inlet port, a gas outlet duct connected to said outlet port, a thin disc closing said outlet duct and having a sharp-edged circular orifice formed in said disc for regulating the speed of movement of said piston by regulating the speed of exhaust of gases to atmosphere therethrough, the inside diameter of said outlet duct being at least fifteen times the diameter of the orifice, and means for supplying gas to the inlet of the actuator at a pressure higher than that necessary to produce critical flow through said orifice at all actuator load conditions.

2. A pneumatic actuator comprising a drive cylinder having a first port at one end and a second port at the other end, a piston movable in said cylinder under the influence of gas admitted into the cylinder, a first conduit connected at one end to said first port, a second conduit connected at one end to said second port, a gas inlet duct

connectable at its outer end to a source of gas under pressure which is at least 30 pounds per square inch in excess of that required to move said piston under maximum load, a gas exhaust manifold for conducting exhaust gas from said cylinder to atmosphere, critical orifice means disposed in the path of gas exhausting from said manifold to regulate the rate of exhaust thereof, said critical orifice means including a thin disc closing the outlet end of said exhaust manifold and having a sharp-edged circular orifice formed in said disc, the inside diameter of the outlet end of said manifold and of said thin disc being about fifteen times the diameter of the orifice, and valve means for connecting said gas inlet duct to said first conduit and for connecting said gas exhaust manifold at its inner end to said second conduit whereby gas is admitted into said cylinder for driving said piston, said valve means also being so constructed and arranged as to connect said gas inlet duct to said second conduit and for connecting said gas exhaust manifold at its inner end to said first conduit for driving said piston in the reverse direction.

3. The construction according to claim 2, characterized further in that said valve means comprises a housing having a valve cylinder formed therein, a valve rod movable in said cylinder, spaced valve discs carried by said valve rod and slidably in contact with the cylinder walls, said cylinder having first and second ports communicating respectively with said first and second conduits, said cylinder having third and fourth ports communicating with said exhaust manifold, said cylinder having a fifth port communicating with said gas inlet duct, said valve discs being so arranged as to be slidable to effect communication between said fifth and second ports for admitting gas into said drive cylinder for moving said piston in one direction and at the same time to effect communication between said first and third ports to allow gas under the influence of said drive piston to exhaust from said drive cylinder into said manifold and through said orifice under conditions of critical flow, said valve discs being so arranged as to be movable also to effect reverse motion of said drive piston.

4. The construction according to claim 2, characterized further in that the valve means comprises a housing having a valve cylinder formed

therein, a valve rod movable in said cylinder, spaced valve disc carried by said valve rod and slidably in contact with said cylinder walls, said cylinder having first, second, third, fourth and fifth ports communicating respectively with said first and second conduits, said exhaust manifold, and said gas inlet duct, whereby upon appropriate movement of said valve rod the drive piston may be moved in either direction as desired, solenoid means for moving said valve rod in either direction as desired, and automatic means for returning said valve rod to a predetermined rest position upon de-energization of said solenoid means.

5. A pneumatic actuator comprising a drive cylinder having first and second ports, a drive piston movable in said cylinder under the influence of gas admitted to the cylinder, a piston rod movable by said piston for driving a load, a source of compressed gas connectable to said cylinder for admitting gas therein through one of said ports, a thin disc-like member closing the outlet from the other of said ports, said disc-like member having a sharp-edged orifice formed therein for regulating the speed of exhaust gas moving therethrough to atmosphere under the influence of said moving drive piston, the inside diameter of said outlet port and said disc-like member being at least about fifteen times the diameter of the orifice, the pressure of said gas admitted to said cylinder being sufficiently greater than the equivalent load pressure required to drive said load as to cause the pressure of exhaust gas in said outlet port on the high pressure side of said orifice to be at least double the pressure on the low pressure outer side of said orifice, whereby the speed of movement of said drive piston may be regulated to remain at a substantially constant predetermined level.
